UNITED STATES PATENT OFFICE.

SAMUEL W. STERN, OF NEW YORK, N. Y.

SMOKING-DOLL.

1,143,458.

Specification of Letters Patent. Patented June 15, 1915.

Application filed December 28, 1914. Serial No. 373,778.

To all whom it may concern:

Be it known that I, SAMUEL W. STERN, a citizen of the United States, and a resident of the city of New York, borough of Brooklyn, county of Kings, and State of New York, have invented a new and Improved Smoking-Doll, of which the following is a full, clear, and exact description.

My invention has for its object to provide a smoking doll having a tube extending from a cigarette in the doll's mouth to a bulb within the doll, and another tube extending from the bulb with branches leading to the doll's mouth and nose so that the bulb may be pressed and smoke may be drawn in through the first tube through a valve at the bulb and the smoke may be exhausted from the bulb to the second tube through a second valve, the smoke being led by the second tube and branches through the doll's mouth and nose.

Additional objects of the invention will appear in the following specification in which the preferred form of my invention is disclosed.

In the drawings similar reference characters refer to similar parts in all the views in which—

Figure 1 is a sectional view showing the body of a doll to which my invention is applied. Fig. 2 is a modified form of the invention showing a fragmentary view of the face of the doll which illustrates the cigarette holder and the tube for exhausting the smoke. Fig. 3 is a fragmentary sectional view showing the modification of my invention; and Figs. 4 and 5 are fragmentary sectional views showing the valves at the bulb.

By referring to the drawings it will be seen that the doll 10 has inwardly extending brackets 11 to which the inlet 12 and the

outlet 13 of the bulb 14 are secured, the bulb 14 at the inlet 12 being provided with a valve 15, the outlet 13 at the bulb 14 being provided with a valve 16.

In the doll's mouth there is a cigarette holder 17 in which there may be disposed the end 18 of a cigarette 19, a tube 20 extending from the cigarette holder 17 to the inlet 12 and a tube 21 extending from the outlet 13 to the nostrils at 22. The body of the doll is flexible so that the bulb 14 may be manipulated from without the doll to draw in smoke through the tube 20 and exhaust the smoke through the tube 21, thereby drawing the smoke through the doll's mouth and exhausting the smoke at 22. In the modified form of the invention the tube 25 leads from the tube 21 to the doll's mouth at 26 so that the smoke will be exhausted not only through the doll's nostril 22, but also through the doll's mouth at 26.

Having thus described my invention I claim as new and desire to secure by Letters Patent:

A doll having a flexible wall, a bulb within the doll and provided with an inlet and an outlet, a valve at the inlet and a valve at the outlet, the bulb being disposed adjacent the flexible wall of the doll so that it may be operated from without the doll, a tube extending from the mouth of the doll to the inlet of the bulb, and a tube extending from the outlet of the bulb to an opening in the doll's head.

In testimony whereof I have signed my name to this specification in the presence of the two subscribing witnesses.

SAMUEL W. STERN.
